(57) **CLAIM**

I claim the ornamental design for a leg sleeve, as shown and described.

DESCRIPTION

FIG. 1 is a perspective view of a leg sleeve, showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The dotted lines in the drawings represent claimed stitching. The dashed lines forming the keys in FIG. 1 are environmental subject matter and form no part of the claim.
